SHOE SOLE

William J. Lutey, Seattle, Wash.

Application May 24, 1947, Serial No. 750,181

5 Claims. (Cl. 36—29)

1

This invention relates to improvements in shoes, and it is in the nature of an improvement upon, and an addition to, the invention that has been described and illustrated in my co-pending application filed on September 26, 1945, under Serial No. 618,639, now Patent No. 2,434,770, wherein I described and illustrated a novel form of cushioning, anti-skid and wear resisting tread for wooden soled shoes.

Explanatory to the present invention, it will be stated that in the above mentioned patent, the tread member was described as being made from a continuous strip of resilient, wear resisting and anti-skid material, helically wound into an open, continuous coil, the coil being laid and secured within a groove or channel that is formed in the under surface of the wooden sole of the shoe. The diameter of the coil in such use is such that the coil, when laid into the channel, extends beyond the surface of the sole a substantial distance. Replacement of the coil, when worn, was not originally intended, for in fact, it would be quite a difficult task to remove the worn coil because of its method of securing. Furthermore, replacement strips are not provided for this purpose and would have to be especially made.

In view of the above, and also in view of the fact that a wooden shoe sole will ordinarily outlive several of the treads as above described, it has been the principal object of this invention to provide replacement treads that can be easily and readily applied by the shoe user, or by an unskilled workman, upon the removal of a worn tread from the shoe.

More specifically stated, the object of this invention is to provide a novel form of mounting plate, and a practical means for the securement of a strip of wear resisting anti-skid material thereto, and also to provide a base member that may be permanently secured to the shoe and to which this plate, equipped with the strip of anti-skid material may be removably secured, so that when the strip becomes worn and replacement is desired, the user of the shoe may easily and readily perform this work.

Still further objects of the invention reside in the details of construction of parts; in the combination of parts and in their mode of use as will hereinafter be fully described.

In accomplishing these and other objects of the invention, I have provided the improved details of construction, the preferred forms of which are all illustrated in the accompanying drawings, wherein—

2

Fig. 1 is a side view of a shoe that is equipped with replaceable tread members in accordance with the teaching of the present invention.

Fig. 2 is an underside view of the shoe, showing tread members as applied to the sole and heel portions thereof.

Fig. 3 is an enlarged, cross-sectional view, taken on line 3—3 in Fig. 2.

Fig. 4 is a perspective view of a strip mounting plate and its base member in disassembled relationship.

Referring more in detail to the drawings.

In Fig. 1, I have designated a shoe in its entirety by reference numeral 10. This shoe comprises a sole portion 11, and a heel portion 12 to which the usual upper 13 of leather, or other suitable material, is secured in the usual manner. The sole and heel portions might be made of leather, or they might be of wood, as were these parts of the shoe which was illustrated in my afore mentioned patent. In the event that wooden soles are used, it is anticipated that a hinge connection may be provided between the heel and sole portions, in the shank portion, as has been indicated at 14 in Fig. 1, and that the parts 11 and 12 be connected across the hinge joint by a flexible strap 15 as shown in Fig. 2.

In the afore mentioned patent, the spirally formed coils were permanently fixed in channels in the wooden sole member, and in the heel member. The present invention contemplates, as the preferred construction, use of a tread unit comprising a base plate, which is to be permanently attached to the sole or heel of the shoe, and replacement tread members that may be detachably secured to the base plate.

The tread unit, for the sole, comprised by the present invention, is designated in its entirety by numeral 16 and the tread unit for the heel is designated in its entirety by reference numeral 17. These tread units are substantially alike in their general elements of construction but they differ in shape, primarily because of the difference in shape of the parts to which they are applied. Each unit comprises a base member, and a removable tread member. A cross sectional view of the tread unit applied to the sole would be almost identical to that of the heel as shown in Fig. 3. Therefore, it is to be understood that the following description of the heel tread unit 17 will apply equally to the tread unit 16 that is applied to the sole.

The heel tread unit comprises a base plate 25 which conforms, as seen in Fig. 2, to the dimensions of the heel portion 12 to which it is se-

cured. This base plate might be stamped from sheet metal, but preferably would be cast of aluminum, or other suitable metal that is light in weight, and it is intended that it be applied flatly against the bottom surface of the heel 12 and permanently secured thereto; for example, by means of tacks 27 as shown in Fig. 3.

The base plate 25, whether die stamped or cast, is formed about its peripheral portion with a continuous downwardly opening channel 30 of substantial width. The tacks 27 which secure the base plate to the heel 12 preferably are driven into the heel through holes 31, provided in the bottom of this channel, and best shown in Fig. 4.

It is shown in Fig. 3, that a recess 32 of substantial size is formed on the top side of this base to reduce the weight of the piece; however, this provision of a recess is not essential to use of the plate.

In order that the anti-skid, resilient, wear resisting element, comprised by the spirally wound strip of material designated by numeral 40, may be easily and readily removed for replacement when worn, the member 40 is affixed as presently explained to a mounting plate that is designated in its entirety by numeral 45. This plate is shown in Fig. 4 as disassembled from its base member 25. The plate 45 has a central portion 45a that is designed to flatly overlie the central portion of the base member that is located within the continuous channel. The edge portions of the plate, designated by 45b, are bent downwardly into the channel close to the inner side walls thereof and then are turned out as a flange 45c that closely overlies the flat bottom surfaces of the channel, as has been clearly shown in Fig. 3.

At regularly spaced intervals along the flange 45c, are outwardly extending wings 49, each of which has a part thereof, 50, adapted to be folded back over the body portion as a securing clip for a loop of the spirally wound strip 40.

The strip 40 is preferably a continuous strip of rubberized fabric of uniform width. Such a strip is quite satisfactory if it is one-half inch wide and adapted to be formed into a helix or coil that may be set down into the channel as in Fig. 3. To assemble this strip 40 with its plate 45, one end of the strip would first be secured between the body portion and back turned portion of one of the wings 49, for example, as at 50x in Fig. 3, then the strip would be formed into a helix or coil and with the forming of the successive loops or convolutions, it would be laid across the body portions of the successive wings 49, and, as each loop is laid across a wing, the clip portion 50 of the wing would be bent upwardly and back to grip and hold the strip. Thus, with the wings properly spaced, a continuous, closed coil as shown particularly in the sole portion of the shoe in Fig. 2, may be formed.

After a strip 40 has thus been secured to its mounting plate 45, the plate may be applied to the base member 25 and secured by one or more screws 60 passed through the middle portion of the plate and threaded into the base member 25 as shown best in Fig. 3.

When it is desired to replace a tread member, the screws 60 are removed, the worn member 40, together with its mounting plate 45, is lifted out and a new tread member put in its place. It is not the intent that a new strip 40 be applied to an old plate, although this could be done.

The only difference between the tread member as applied to the sole and that applied to the

heel is the difference in size by reason of the different dimensions of the sole and heel; the base member of the unit applied to the sole naturally would be curved to conform to the curvature of the sole, and the plate 45 of the tread member would have more attaching screws, as has been illustrated in Fig. 2.

With the shoe so equipped, it will be understood that the life of the shoe will be extended indefinitely. Such replacement members may be made in standardized sizes for shoes of different size and may be applied either to leather soled or wooden soled shoes.

It is anticipated that the present replacement tread members might also be applied to wooden soled shoes as provided with channels as shown in my co-pending application. In such case, the base members, as used in the present instance would not be required, but the tread members, comprising the plates 45 with resilient strip attached, would be applied directly to the wooden sole and heel portions of the shoe, and secured by short screws driven into the sole or heel portions.

It is also to be understood, that in the use of such replacement tread members, I do not wish to be restricted to the particular form of helically wound strip, but anticipate that various forms of strips, either solid, coiled, or in separate pieces, might be secured to the plate, to be seated and held thereby in the channels and serve the same purpose as the helically wound strip shown in the present drawings.

Shoes equipped with treads of this kind are especially desirable for use by persons working on concrete floors, such as in cold storage plants, or in other places where the floors are apt to be slippery or cold. The tread not only adds life to the shoe but prevents slipping, adds comfort and keeps the shoe out of the dampness of the floor.

Having thus described my invention, what I claim as new therein and desire to secure by Letters-Patent is:

1. A tread for shoes and the like comprising a base member having a continuous, downwardly opening channel formed therein about its peripheral portions and a replacement tread member comprising a flat metal plate adapted to be disposed against the island portion of said base member that is enclosed within the continuous channel, means for detachably securing the said plate to the island portion; said plate having its peripheral portion bent upwardly into the channel adjacent its inner wall and formed with a horizontal flange that overlies the base surface of the channel and a resilient tread strip fixed on said flange and held seated in said channel thereby and extending from the channel beyond the undersurface of the base member.

2. A tread as recited in claim 1 wherein the peripheral portions of said plate of the replacement tread member are bent to extend into the said channel and are formed with flanges adapted to closely overlie the bottom surface of the channel, and wherein the said tread strip comprises a continuous strip of resilient material, formed into a helical coil and attached to said flanges to lie within the channel and to extend from the channel beyond the under surface of the base member.

3. A tread unit for shoes and the like, comprising a base member adapted for fixed securement to the bottom of the shoe and having a downwardly opening channel formed therein and a replacement tread member comprising a plate

adapted to be detachably secured to the bottom of the base member and having an upturned peripheral portion extended into the said channel closely along the inner wall thereof to adjacent the bottom surface thereof, and then formed with a flange that overlies the bottom of the channel, and a resilient tread member fixed to the flanged portion of the plate and held thereby in the channel and extending from the channel beyond its under surface and limited in lateral spreading by the outer wall of the channel and the upturned peripheral portion of the plate.

4. A tread unit for shoes and the like, comprising a base member adapted to be fitted to the shoe bottom and to be permanently secured thereto; said base member having a continuous channel formed therein about its peripheral portion; and a replacement tread member comprising a flat plate fitted flatly to the bottom surface of the base member within the continuous channel, and screws removably applied through said plate and into said base member for securement of the plate thereto; said plate having its peripheral portions bent upwardly to lie against the near channel wall, and then outwardly flanged to closely overlie the channel bottom, and a resilient tread strip, formed into a helix and disposed in said channel about the plate and permanently fixed to said flanged portion within the base of

the channel; said strip extending outwardly from the channel as a cushioning, anti-skid tread member and removable from the shoe with the removal of the plate.

5. In a tread of the character described, a replacement tread member comprising a mounting plate having a peripheral flange with wings extending outwardly therefrom at regularly spaced intervals, and a tread comprising a continuous strip of resilient material, wound into an open helical coil, and applied lengthwise about the said plate overlying said wings; each of said wings having a part thereof bent over and against a part of the helically wound strip to secure it to the wing.
